UNITED STATES PATENT OFFICE.

EDWARD P. COLE, OF CHICAGO, ILLINOIS.

COOKING-RANGE.

1,392,482.

Specification of Letters Patent.

Patented Oct. 4, 1921.

Application filed August 9, 1919. Serial No. 316,478.

To all whom it may concern:

Be it known that I, EDWARD P. COLE, a citizen of the United States, residing at Chicago, in the county of Cook and State of Illinois, have invented certain new and useful Improvements in Cooking-Ranges, of which the following is a specification.

My invention relates to cooking stoves or ranges such as are universally used for domestic purposes, and more particularly to stoves of the type known as "high oven" stoves or ranges, in which the burning gases resulting from the combustion of a suitable fuel, such as wood or coal, are conducted from the firebox through a flue to the lower side of an oven elevated above the cooking top in which the usual stove lids are arranged. The object of my invention is to improve the combustion of the fuel and the distribution of heat to the oven in such stoves, and to avoid any undue and excessive heating of bottom wall of the oven at a point immediately above the top of the flue which conducts the heated gases to the oven structure. A further object is to produce an oven which shall not only be efficient for the purpose described but which shall be equally efficient and desirable for the use of gas as a fuel by the addition of a suitable gas burner arranged in the lower part of the oven. With the foregoing and incidental advantages and also with improvements in structural details in view, I have designed and invented the novel stove hereinafter described, and illustrated in the accompanying drawings forming part of this specification, the essential elements of my invention being more particularly pointed out in the appended claims, it being understood, however, that variations and modifications of the specific construction disclosed are possible without departing from the substance of my invention, or the scope of the claims.

Of the drawings Figure 1 is a perspective of the upper portion of a cooking stove which includes an oven embodying my invention; Fig. 2 is a central vertical cross-section of such oven; and Fig. 3 is a fragmentary vertical section of the upper portion 50 of said oven, on the line 3-3 of Fig. 2,

The same reference characters indicate the same parts in all the figures of the drawing. Since my invention relates mainly to the oven of a range of the type mentioned, it will suffice to explain with reference to the 55 stove that the flame and heated gases from the firebox 1 enter the closed space underneath the cooking top 2, from which they are conducted upwardly through the flue 3 to the lower part of the oven structure, 60 which latter is suitably supported upon the stove, as by means of the flue itself and bracket 4 connected to the stove frame beneath.

The flue 3, in order that the burning 65 gases therein may not be cooled in passing therethrough, is lined with a layer of asbestos 3^a which is confined in place by a cast-iron grill 3^b which protects and supports the asbestos. 70

The oven, arranged at the top of the flue 3, is formed with an outer casing 5, within which is arranged an inner casing 6 consisting of a bottom wall 7, side walls 8-8 and a top wall 9 extending from the front wall 75 to the rear wall of the casing 5 and inclosing the cooking compartment which constitutes the oven proper. At top and bottom and on both sides the walls of the casing 5 and the walls of the box 6 are spaced apart, leaving a closed passage way around the oven 80 communicating with the flue 3 and with the upper or outlet flue 10 leading to the chimney. The front side of the oven 6 is provided with the usual oven door 11. Below 85 the bottom wall 7 of the oven and extending from the front to the rear wall of the casing 5 is secured a spreading partition 12^a the sides of which are connected at their edges to the sides of said bottom wall and the central depressed angle or valley of which extends to a plane about midway between the bottom 7 of the oven and the bottom of the casing 5. In the front wall of the casing 5, immediately above the partition 5, is formed 90 an opening 12 through which extends the supply pipe 14 of the gas burner 15.

In order to provide means for varying the amount of air permitted to pass into the compartment between the bottom wall of the 100

oven and the partition 12^a, and to provide for automatically admitting a maximum supply of air when the gas is turned on, and a lesser adjustable supply when the gas is turned off, I have provided a door 13 for said opening which is connected by a link 20 with the handle 21 of the burner valve, the arrangement being such that the door is opened when the valve is turned to open the 10 valve and closed when the gas is shut off. The door is formed with openings governed by a slide 22, by means of which the amount of air passing into the compartment may be controlled as desired when the door 13 is 15 closed.

The bottom of the oven is formed with a series of holes 17 along its side edges to provide for the passage of hot gases from the gas burner and of air entering through or 20 past the door 13 into the oven. Between the top wall 9 of the oven and the top wall of the casing 5 and extending across the entrance to the upper flue 10 is arranged an angular partition 18 forming a soot guard, 25 the apex of which lies immediately beneath the casing wall and the side edges of which are imperforate and connected with said top wall 9. The front end of this partition is continuous with the front wall of the casing 30 wall but the rear end does not extend to the rear casing wall, thus leaving a passage way to the flue through which gases may escape from the top of the oven after passing through a series of orifices 19 formed in the 35 top wall 9 of the oven beneath the front end of the partition 18.

The flame and heated products of combustion passing through the flue 3, which in effect forms a continuation of the firebox or 40 combustion chamber, will impinge upon the lower side of the angular partition 12^a, heating it to redness over a spot which is above and in alinement with the flue, when the fire is burning briskly and producing a cooking 45 temperature. This highly heated spot acts upon particles of combustible solid matter and gases impinging upon it and conduces to perfect combustion of the fuel. The heat is to some extent distributed upwardly and 50 outwardly by conduction through the spreading sides of the partition 12^a, and the air within the compartment, by contact with the heated partition wall and radiation therefrom, is effectively heated and rises 55 through the holes 17, creating an upward draft of heated air through the oven, the amount of air entering through the openings 22 being regulated according to the intensity of the fire and the temperature of the air. 60 Since the heated air must pass out through the openings 19 at the front side of the oven near the top of the oven door the temperature in the front part of the oven will be maintained notwithstanding some leakage of 65 air around the door.

The angular, elongated shape of the soot guard 18, arranged transversely of the path of the products of combustion and extending diametrically of the outlet flue conduces to dividing the draft equally on the sides 70 of the oven, and the arrangement of the openings is such as to most efficiently protect the oven from the entrance of soot and ashes from the flue.

I claim:

1. In a stove having a firebox and flue, an oven structure comprising a casing communicating with said flue at its bottom and having an outlet flue at its top, an oven proper arranged within said casing and separated therefrom at its sides and top by heating passages communicating with said flues, and a partition inclosing a compartment at the bottom of said oven and above the bottom of the casing above said first- 80 mentioned flue, an opening being provided permitting the admission of outside air into said compartment, said oven being provided with openings at top and bottom arranged to permit passage of air from said compartment to said outlet flue, and a hollow shield secured to the top of said oven above its top openings and having imperforate sides arranged transverse to the path of products of combustion passing over the top of the oven 85 into said outlet flue, said shield opening into the flue passage between the casing and oven.

2. In a stove having a firebox and flue, an oven structure comprising a casing communicating with said flue at its bottom and having an outlet flue at its top, and oven proper arranged within said casing and separated therefrom at its sides and top by heating passages communicating with said flues, and a partition inclosing a compartment at the bottom of said oven and above the bottom of the casing above said first- 100 mentioned flue, an opening being provided permitting the admission of outside air into said compartment, said oven being provided with openings at top and bottom arranged to permit passage of air from said compartment to said outlet flue and an inverted hollow trough forming a soot guard secured to the top of said oven above its top openings 105 and having imperforate sides arranged transversely of the path of products of combustion passing into said outlet flue, said top oven openings being arranged at the front end of said guard and the rear end of said 110 guard being open.

3. In a stove having a firebox and flue, an oven structure comprising a casing communicating with said flue at its bottom and having an outlet flue at its top, an oven 125 proper arranged within said casing and separated therefrom at its sides and top by heating passages communicating with said flues, and a partition inclosing a compartment at the bottom of said oven and above 130

the bottom of the casing above the said first-mentioned flue, an opening being provided permitting the admission of outside air into said compartment, said oven being provided 5 with openings at top and bottom arranged to permit passage of air from said compartment to said outlet flue and an angular soot

guard having its apex arranged diametrically of said outlet flue and transversely of the path of the products of combustion and 10 inclosing the top openings of the oven, at least one end of said guard being open.

EDWARD P. COLE.
